UNITED STATES PATENT OFFICE.

BYRON G. TARKINGTON, OF SHOREWOOD, AND OTTO F. WINSINGER, OF MILWAUKEE, WISCONSIN, ASSIGNEES TO AMERICAN RESISTOR CORPORATION, OF PHILADELPHIA, PENNSYLVANIA, A CORPORATION OF NEW YORK.

DESIGN FOR AN ELECTRICAL HEATING APPLIANCE.

Application filed January 10, 1927. Serial No. 20,329. Term of patent 7 years.

To all whom it may concern:

Be it known that we, BYRON G. TARKINGTON and OTTO F. WINSINGER, citizens of the United States, residing at Shorewood and Milwaukee, respectively, both in the county of Milwaukee and State of Wisconsin, have invented a new, original, and ornamental Design for Electrical Heating Appliances, of which the following is a specification, reference being had to the accompanying drawing, forming a part thereof.

In the drawings:

Fig. 1 is a view in side elevation of an elec-

trical heating appliance showing our new design.

Figs. 2 and 3 are views in front and rear elevation, respectively, of the electrical heating appliance of Fig. 1.

We claim:

The ornamental design for an electrical heating appliance, as shown.

In witness whereof, we affix our signatures hereto.

BYRON G. TARKINGTON.
OTTO F. WINSINGER.
